UNITED STATES PATENT OFFICE.

FRANK WILCOMB, OF PAWTUCKET, RHODE ISLAND, ASSIGNOR TO HEMPHILL MANUFACTURING COMPANY, OF CENTRAL FALLS, RHODE ISLAND, A CORPORATION OF RHODE ISLAND.

SPRING-NEEDLE KNITTING-MACHINE.

Specification of Letters Patent.

Patented Oct. 30, 1917.

1,244,673.

Application filed April 14, 1914, Serial No. 831,797. Renewed January 13, 1917. Serial No. 142,823.

To all whom it may concern:

Be it known that I, FRANK WILCOMB, citizen of the United States, residing at Pawtucket, Rhode Island, have invented certain 5 new and useful Improvements in Spring-Needle Knitting-Machines, of which the following is a specification.

My invention concerns particularly a needle beard pressing and a yarn feeding 10 organization for spring needle knitting machines, and it consists in the features and combination and arrangement of parts hereinafter described and particularly pointed out in the appended claims.

15 In the accompanying drawings

Figure 1 is a diagrammatic plan view of a portion of the needle circle of a circular spring needle knitting machine, the needles being shown in part in section and in part 20 in plan, and with the presser bits, yarn guard bits and web holders in their proper relation;

Fig. 2 is a plan view of a yarn feeding mouth showing its relation to the needles 25 and other elements of Fig. 1;

Fig. 3 is a front view of the yarn feeding mouth;

Fig. 4 is a sectional view of the yarn feed mouth;

30 Fig. 5 is a plan view of part of the knitting head illustrating features relating to the yarn feed mouth;

Fig. 6 is a view of the knitting elements, needles, yarn guard bits, pressers, and web 35 holders in the relation assumed by them at the yarn feeding point, the yarn feeders and needle beard pressers being retracted;

Fig. 7 is a view similar to Fig. 6 with the 40 yarn guard bits advanced to hold the yarn close to the needle stems, and with the presser bit advanced from its retracted position toward pressing position;

Fig. 8 is a view similar to Figs. 6 and 7, with the yarn guard bits advanced and with 45 the presser bit advanced and pressing the needle beard;

Fig. 9 is a diagrammatic front view of the needles, pressers, and yarn guard bits, and the yarn feed mouth showing the drawing 50 and evening of the loops across the tops of the web holders. This view being on a larger scale than Fig. 1 differs therefrom in number of needles lying between the portion of the feed mouth and the point where pressing is done, this being because of the lack

of space and the fact that the view is of a diagrammatic character. In other words the knitting wave in Fig. 9 has been condensed in respect to that which would appear from the use of the same number of needles as 60 illustrated in Fig. 1.

Fig. 10 shows a presser and a feeder.

Radially sliding pressers 1 are employed one for each needle. These may be operated inwardly for pressing either by a cam means 65 or by a presser wheel. When a presser wheel is used it operates against the butts of the presser bits, forcing them against the needles to press the beard, and in addition to these sliding pressers I employ sliding yarn guard 70 bits 3 of about the same shape as the pressers with but slightly longer depending front ends 4. The yarn guard bits are arranged to slide in the same grooves with the pressers, and I prefer to have a yarn guard bit 75 on each side of each presser, though the invention is not limited in this respect.

The yarn guard bits 3 are adapted to slide toward the needles far enough to hold the 80 yarn close to the stems thereof, but not close enough to crimp the yarn or to sink loops as would be done by sinkers. With the two yarn guard bits, one on each side of the presser, a space between the two guard bits is provided where they project beyond 85 the pressers, into which opening the needle beard passes as it travels downward to grasp the yarn. The pressers and guard bits can be operated by providing suitable operating

means to have independent action at any 90 desired place in the needle circle, and the yarn guard bits may be worked simultaneously with the pressers whenever desired. The pressers and guard bits have butts projecting from their stems for engaging cam paths, 95 the pressers having two butts 5, 6, and the guard bits having one butt. The guard bit butts 7 alone with the forward butts 5 of the pressers, and in the cam plate 10 covering the pressers and guard bits there are 100 two cam paths 8 and 9 in which the butts travel. At the point *a* where yarn is fed to the needles, the pressers and guard bits are retracted to permit yarn to be laid in front of the guard bits as near down on the 105 top of the web holders 11 as possible. This position of the parts is shown in Fig. 1 and in Fig. 6. As the machine revolves, the yarn guard bits advance after the manner of sinkers, but the advance is stopped before the 110

guard bit is advanced enough to crimp the yarn or to bring any frictional restraint thereon. This position of the yarn guard bits is indicated in Fig. 1 from the point *b* 5 to the point *c*. It is also indicated in Figs. 7 and 8. The needles after having received the yarn against their stems move downward in the same way as independently operated latch needles. The beards travel down between the guard bits without coming in contact with the pressers, which are at this time retracted. When the needles' downward travel is low enough for the needle beard 10 to have seized the yarn, the pressers are then advanced, as shown in Fig. 8, and at *c'*, Fig. 1, to press the beard without further advancement of the yarn guard bits. Immediately after the needle is pressed, the pressers and yarn guard bits may be retracted as shown at *d*, Fig. 1, and may remain retracted until the next feeding operation takes place.

In addition to the functions described above, the guard bits perform also another function, *i. e.*, to control the yarn in the narrowing and widening operations in making heels and toes, and prevent the surplus yarn, resulting from the constant changes in the direction of rotation of the needle circle, 25 from being caught under the web holder hooks. Therefore during reciprocating knitting these guard bits will contact with and hold the yarn close to the stems of the needles during the reciprocations of the cylinder.

30 In conjunction with the guard bits and pressers I have devised a new form of yarn feeder mouth, and means for directing the yarn into the mouth when changing from one yarn to another or for splicing or reinforcing. It is important that the yarn be fed as low down on the web holder as possible to prevent any wavering of the yarn, sometimes called ballooning, and also to lay 35 it in front of the yarn guard bits.

I have therefore provided a yarn feeding mouth piece 12 adapted to deliver the yarn close to the stem of the needle and as low as possible to make it lie near the top of the 40 web holders 11. This feed mouth has a base portion 13 which fits upon the cam ring, and extending up along the sides of this base portion are the sides 14. At its inner 45 end the feed mouth has a depending inwardly inclined portion 18', the lower end of which is close to the needle stem and to the top of the web holders.

This depending portion is provided with a mouth or opening defined by edges 15 inclining downwardly and outwardly in 50 respect to the center of the mouth piece, and this opening with its inclined edges extends to near the bottom of the depending portion and below the floor or base portion 13 of 55 the mouth piece. This construction leaves

a cross bar 16 at the bottom of the downwardly flared opening. The mouth piece is secured to the cam ring by screws, as shown in Fig. 2.

From this construction it will be seen 70 that the corner at 17 at the bottom of the inclined guiding edge is close to the needles and to the tops of the web holders.

The yarn passes from the yarn finger 21 through the opening in the mouth piece, 75 and owing to the inclined guiding wall 15 of the mouth piece the yarn is deflected downward into the lower corner 17 thereof in close proximity to the web holder tops, and is laid between the needle and the guard 80 bits. The mouth piece has two walls inclined, as described, to permit of feeding the needles as they travel in either direction for round knitting, or reciprocating knitting, as in the case of making heels and toes 85 of stockings.

The lower guard or cross bar 16 is necessary to hold the yarn from entangling with the web holders and guard bits as the machine travels first one way and then 90 the other.

In connection with the mouth piece, a device 19 is employed for guiding the yarn into the mouth piece as the yarns are changed or when splicing and reinforcing is 95 done. This device may be of various forms, but in the particular construction shown it consists of a finger or rod extending up from the base of the mouth piece. This finger is detachable from the mouth piece, it 100 being attached as shown in Fig. 5 to the clearing plate bracket 20 shown in my application #804,025, filed December 1, 1913, and when the bracket and clearing plate are lifted away from the needles for any purpose as, for instance, transferring ribbed tops to the needles, the finger 19 is lifted away from the mouth piece to avoid interfering with the transfer cup. When the clearing plate and bracket are lowered, the 105 finger 19 falls into a recess or hole 21' in the mouth piece, so that the yarn traveling over the surface of the mouth piece will not get caught under the guard finger. The clearer plate, together with the 110 guard or guide finger 19, is carried by an arm 20 pivotally mounted to any suitable part of the frame so that it may be swung up and away from within the needle circle. 115

This guard finger performs the function 120 of directing or controlling the inoperative yarns which are held in a high position while inoperative, and when a yarn feed finger drops from its elevated inoperative position and lowers the yarn into the needles, the guard wire or finger 19 prevents 125 the yarn from passing over the top of the inclined wall of the mouth piece.

In other words, the guard finger 19 prevents any yarn, when raised to 130

erative position, from assuming such a position in extending from the yarn feed finger to the clamping plate at the center of the needle circle, as would cause this yarn, when lowered, passing over the top of the mouth piece without getting into the inner opening thereof to be guided by its inclined edge or wall 15.

It will be seen that the mouth piece above described is fixed to the cam plate of the machine, and is low enough in structure and position to lie considerably below the upper ends of the needles when these are elevated.

This construction will permit the use of a transfer cup for transferring ribbed tops, and by using a guard finger or wire 19 the advantages of a high mouth piece are obtained without the objection existing thereto of preventing the use of transfer cups, for as above stated when the machine is working any yarn which is raised out of work will be controlled by the guard finger and directed to the inclined guiding wall of the mouth piece when again thrown into work by the lowering of its finger as 21, but when transferring is to be done the said wire or finger will be raised and entirely removed from its working position at the same time that the central clearing plate is swung upwardly and to one side from within the needle circle. In effect therefore the construction presents a high mouth piece when yarn feeding is going on, and a low mouth piece when transferring tops is to be done. In Fig. 9 a number of yarn feed fingers are shown in their elevated positions to hold their yarns out of work, one yarn finger, however, being in its lowered position to place its yarn in work. It will be seen from this figure that the width of the mouth piece opening is less than the combined width of the yarn fingers. Notwithstanding this, the yarns will be guided into the mouth piece when lowered by the guide or guard finger or wire.

The arrangement of the yarn guard bits independent of pressers presents advantages inasmuch as the guard bits may be operated entirely independent of the pressers, and vice versa. There is an advantage in being able to adjust the guard bits for different sizes of yarn and different gages, independently of the pressers, and there is an advantage in being able to adjust the pressers for different sizes of needles independent of the guard bits. Besides, a decided advantage in construction exists, as the guard bits may be made of thin, well tempered metal smooth on the feeding end, and the pressers likewise may be made independently and smooth and uniform. The independence of the yarn guard bits in respect to the pressers and the ability to control these yarn guard bits as may be desired is an essential advantage.

I have referred to the advancement of the presser to press the needle beards. This might not always be true, as the needle beard of a very coarse gage machine might require that the presser be retracted slightly, 70 or to remain stationary when it is to perform its pressing action to prevent pressing too hard, but generally speaking the pressers are advanced against the needle beard from a normally retracted position. 75

In the plan view, Fig. 1, I show the yarn guard bits advanced and the pressers partly advanced as soon as they have passed the feeder mouth piece. The pressers being advanced or partly advanced at this point has no effect whatever, and if desired they might be left retracted, but my pressers and guard bits both have butts near the center of the stem and the advancement of one of the elements necessarily advances the other. 85 It will be understood that this center butt of the presser being of about the thickness of the needle and therefore strong, and the guard bits being very thin and consequently having weak butts, the presser butt supports the guard bit butt against the thrust of the cams. At the point *f* just in advance of the pressing point *c'* the pressers are retracted by their rear butts working in the cam groove at *e*. The object of this retraction of the pressers is to permit the needle beard to pass down and seize the yarn without coming into contact with the pressers at all. When the needle has reached a point for pressing, the pressers are advanced by their rear butts independently of the yarn guard bits. After pressing, the guard bits and pressers are immediately retracted by their center butts so that as the needles draw the loops down into the fabric 95 the guard bits are so far retracted that they do not obstruct free passage of the yarn. The pressers and guard bits may then be left in retracted position until the next feeding operation takes place. 100

It will be seen that the two grooves in the cam plate are adapted to give the pressers and yarn guard bits their necessary independent or unitary movements. The pressers are operated in most part by their outer butts moving in the outside cam groove. Their middle butts are provided to afford lateral support for the butts of the thin yarn feeders. As the pressers are retracted at the point *f* I provide the inner cam groove 120 with a space at *f'* to allow for this retraction. The yarn guard bits, however, remain forward at this point. The web holders are independently and individually operated as in my previous application for Letters 115 Patent of the United States above referred to.

My invention in one aspect concerns the use of yarn guard bits for the needles, combined with web holders and some suitable 130

presser means. The web holders and the presser means may be of various forms, but in the particular construction shown the presser means consist of the radially sliding bits above described and the radially sliding web holders.

The upper surfaces of the web-holders serve as supports for the yarn against downward movement and the yarn guard-bits act to retain the yarn laterally against the needle shanks, but are not the means for preventing vertical movement thereof.

I claim as my invention:—

1. In combination in a spring needle knitting machine, independently operated sliding spring needles, web holders, individual needle beard pressers independently operated, and individual yarn guard bits independently operated to retain the yarn close to the needle stems without sinking and thereby providing a space for the needle beard to pass downward between the guard bits and seize the yarn, substantially as described.

2. In combination in a spring needle knitting machine, independently operated sliding spring needles, web holders, individual needle beard pressers independently operated and individual yarn guard bits independently operated to hold the yarn close to the needle stems without sinking and thereby providing a space for the needle beard to pass downward between the guard bits and seize the yarn, said pressers being interposed between the yarn guard bits, substantially as described.

3. In combination in a spring needle knitting machine, independently operating needles, web holders, individual pressers, and yarn guard bits arranged on each side of the pressers and forming a space between them in advance of the pressers for receiving the needle beards, said bits holding the yarn without sinking close to the needle stems and thereby providing a space for the needle beard to pass downward between the guard bits and seize the yarn, substantially as described.

4. In combination in a spring needle knitting machine, independently operated needles, web holders, individual pressers, and individual yarn guard bits holding the yarn close to the needle stem without sinking, said pressers being located in the same grooves with the guard bits, said yarn feeders and pressers having their nose ends guided between the web holders.

5. In combination in a spring needle knitting machine, independently operated needles, web holders, individual yarn guard bits holding the yarn against the needle stems without sinking individual pressers, the presser and the yarn guard bit for the same needle being arranged in the same groove, and means for operating the press-

ers and yarn guard bits independently, substantially as described.

6. In combination in a spring needle knitting machine, independently operated spring needles, web holders, individual pressers independently operated, and individual yarn guard bits independently operated and holding the yarn against the needle stems without sinking, said yarn guard bits being interposed between the web holders, substantially as described.

7. In combination in a spring needle knitting machine, independently operated spring needles, web holders, radially sliding individual pressers, and radially sliding individual yarn guard bits for holding the yarn close to the stem of the needle without sinking, substantially as described.

8. In combination in a spring needle knitting machine, independently operated spring needles, web holders, radially sliding individual pressers, and individual yarn guard bits sliding radially and independently of the pressers and projecting beyond the pressers to form a space to receive the needle beards, said yarn guard bits holding the yarn against the needle stems without sinking, substantially as described.

9. In combination in a circular spring needle knitting machine, spring needles, radially sliding individual pressers, radially sliding individual yarn guard bits holding the yarn against the needle stems without sinking, and the independent cams for operating respectively the pressers and yarn guard bits, substantially as described.

10. In combination in a spring needle knitting machine, independently operated spring needles, web holders, yarn guard bits for retaining the yarn close to the needle stems without sinking and a yarn feed mouth having a portion depending close to the needle stems and to the tops of the web holders and between the inner ends of the yarn guard bits and said needle stems, said yarn mouth having inclined guiding edges for the yarn, substantially as described.

11. In combination in a spring needle knitting machine, independently operated spring needles, web holders, yarn guard bits for retaining the yarn close to the needle stems without sinking and a yarn feed mouth having a portion depending close to the needle stems and to the tops of the web holders and between the inner ends of the yarn guard bits and said needle stems, said yarn mouth having inclined guiding edges for the yarn, and individual pressers.

12. In combination in a circular knitting machine, spring needles, web holders, guard means to retain the yarn close to the needle stems without sinking, a yarn feed mouth having an inner depending portion extending close to the needles and web holders, and below the top of the guard means, said de-

pending portion having a downwardly flaring opening with inclined lateral guiding edges for the yarn and having a cross bar or guard at its lower part, the said inclined edges extending down to said cross bar, substantially as described.

13. In combination in a spring needle knitting machine, web holders, radial individual pressers, radial individual yarn guard bits, means for giving the pressers and yarn guard bits radial sliding movement, and a yarn feed mouth, said pressers and yarn guard bits being retracted to pass the yarn feeder mouth, substantially as described.

14. In combination in a circular knitting machine, needles, a yarn feed mouth and a removable yarn guide entering an opening in the yarn feeding mouth when in operative position, and a movable support for said yarn guide, said guide being removed from said opening when its support is moved to clear the needles for transferring, substantially as described.

25 15. In combination in a stocking knitting machine, a needle cylinder having rotary and reciprocating movement, web holders, pressing means, and yarn guard bits to hold the yarn close to the stems of the needles without sinking, said guard bits preventing

the surplus yarn from being caught by the web holders during reciprocating knitting, and presenting spaces for receiving the needle beards when seizing the yarn, substantially as described.

16. In combination in a spring needle knitting machine, independently operated sliding spring needles, web holders, presser means, and one or more yarn guard bits for each needle independent of the web holders to retain the yarn close to the stems without sinking, said guard bits having spaces between them for the passage of the needle beards, substantially as described.

17. In combination in a spring needle knitting machine, independently operated sliding spring needles, web holders, presser means, and one or more radially movable yarn guard bits for each needle to retain the yarn close to the needle stems without sinking, said guard bits being elements independent of the web holders, substantially as described.

In testimony whereof, I affix my signature in presence of two witnesses.

FRANK WILCOME.
